J. McDONALD.
BRICK MACHINE.

No. 67,561.

Patented Aug. 6, 1867.

United States Patent Office.

JOHN McDONALD, OF NEW YORK, N. Y.

Letters Patent No. 67,561, dated August 6, 1867.

IMPROVED BRICK MACHINE.

The Schedule referred to in these Letters Patent and making part of the same.

TO ALL WHOM IT MAY CONCERN:

Be it known that I, JOHN McDONALD, of the city and county of New York, and State of New York, have invented certain new and useful improvements in Brick-Presses; and I do hereby declare that the following is a full and exact description thereof.

My invention relates to that class of brick-presses which are adapted for re-pressing the material after it has been previously pressed or moulded, and subsequently dried or partially dried. I will first describe what I consider the best means of carrying out my invention, and will afterwards designate the points which I believe to be new. The accompanying drawings form a part of this specification.

Figure 1 is a side view of my press with the platen raised.

Figure 2 is an end elevation, partly in section, representing the press in the same condition.

Figure 3 is a side elevation, representing my press with the platen depressed.

Similar letters of reference indicate like parts in all the figures. Tints are employed merely to aid in distinguishing parts, and do not indicate materials. The materials of the whole may be iron and wood.

A is a framing of wood, mounted on wheels *a*, to make it more conveniently propelled, and having an upright guide, A 1, of cast iron, properly compressed, and securely bolted to the other portion of the framework. B is a slide, which embraces the upright guide A 1 at its upper end, and is guided near its lower end by passing through the framework A, which carries a stout horizontal arm, B 1, which forms a platen to the press. C is a link, which connects the piece B to a crank in the rocking-shaft D, which latter is operated by the tender by means of a lever, D 1. E is a movable bed-piece, supported on a spring, *e*, with liberty to rise and sink to a small extent, as represented. The partially-dried brick is placed upon the upper surface of the part E, which latter should be very nearly as large as the brick. The descent of the platen B 1 compresses the brick flatwise between them. The spring *e* yields by its elasticity as the platen descends, and forces the brick down upon the bed-piece E, and thus allows the latter to be supported upon the solid framing A, which surrounds the opening. As the platen rises the brick and movable bed E rise with it to a limited extent. When the bottom flanges E 1, which extend outward from the sides of the base of the piece E, meet the corresponding flanges, which project over them from the part A, its upward motion is arrested, and the continued ascent of the platen liberates the brick, and allows it to be removed and another placed in its stead, after which the operation is repeated. G 1 G 2 are levers, turning on centres *g*, which are mounted in the sides of the platen B 1. H is a corresponding lever, mounted on the pivot *h*; carried also on the platen B 1. J J J are links, connecting the upper ends of these three levers to the extremity of the arm A 2, which is secured on the upright A 1 at a point above the highest travel of the slide B. This arm A 2 is made adjustable by means of the set-screw, as represented, so that it may be changed up and down on the upright A 1, and thereby vary the conditions under which the levers G 1, G 2, and H are operated. All these parts are so proportioned and adjusted, as represented, that, while the platen B 1 compresses the upper face of the brick, the lever G 1 shall compress one of its edges, the lever G 2 compress the opposite edge, and the lever H compress one end. It is practicable, by adding another lever, and making the framework more open, as will be readily understood by mechanics, to also provide an additional lever, and compress the end opposite the lever H; but I do not esteem this generally necessary.

The re-pressing of bricks as the operation is usually performed is imperfect, by reason of the action being only on the two broad faces—the upper and lower faces—when the brick lies flatwise. My press, by acting on the edges at the same time, makes a more uniform pressure of the material, pressing it in all directions. My mechanism, consisting of the three levers, mounted on pins, moving with the platen, and connected by links to a common adjustable fixed point, for effecting these movements, is very simple, and may be cheaply constructed and easily kept in order.

The movements of the movable bed E, under the action of the spring *e*, accomplish the highly important end of causing the brick to ascend with the platen while the levers G 1, G 2, and H are being slowly turned on their respective pivots to release the edges of the brick from pressure. In the absence of this movement there would be a tendency to crumple the edges, but for the fact that the bed E lifts the brick during the early portion of the rise of the plate, and follows it until the respective levers have entirely released their hold on the edges

and end of the brick, and leaves the material at rest without exposing it to any strain other than the direct compression.

Having now fully described my invention, what I claim as new therein, and desire to secure by Letters Patent is as follows:

1. I claim, in combination with the platen B 1, or its equivalent, adapted to press the brick flatwise, the employment of levers adapted to press the bricks on their edges, as G 1 G 2, with or without the end-pressing lever H, substantially as herein specified.

2. I claim, in connection with the above, the within-described method of operating said levers, that is to say, mounting the said levers on pivots g h, carried on the platen, and connecting the upper ends of the levers of the adjustable piece A 2, or its equivalent, all arranged for joint operation as herein specified.

In testimony whereof I have hereunto set my hand in the presence of two subscribing witnesses.

Witnesses:

W. C. DEY,

C. C. LIVINGS.

JOHN McDONALD.
